INVENTOR

GEORGE W. ACKERMAN
BY *Minnolas.*

ATTORNEY

UNITED STATES PATENT OFFICE.

GEORGE W. ACKERMAN, OF NEW YORK, N. Y., ASSIGNOR TO ACKERMAN DOOR INTERVIEWER CORP., OF NEW YORK, N. Y., A CORPORATION OF NEW YORK.

GRILLE.

Application filed April 23, 1927. Serial No. 186,115.

An object of the invention is to provide a grille capable of a wide range of utility, but finding one of its preferred embodiments in a device for use on apartment doors. 5 An object of the invention is to provide a device of this character which will permit the occupant of an apartment to observe applicants for entrance without opening the door, to pay bills, or to carry on conversation through the grille without any danger of an intruder gaining entrance or inserting his hand through the grille to open the door from the inside. The grille of the present invention represents a material improvement 10 over the grille disclosed in my copending application Serial No. 126,055; particularly in that the cost of manufacturing the grille has been materially reduced, and the operation of attaching the grille to a door 15 has been considerably simplified and facilitated.

It will be recalled that in my prior application, two frame members were laid against opposite sides of a door, these frame members encircling a previously formed recess and being connected together by securing devices passed through the door. One frame member carried a grating and the other carried a closure.

20 In accordance with the present invention, the device consists of two main parts instead of three, to wit: a grille-bearing frame member, to which the closure is directly connected. The device is thus of unitary, rather than built-up construction, and may be emplaced as a unit in a previously prepared opening in the door. In fact a workman standing on the outside of a door may attach the grille unit by the simple expedient of 25 fitting it into the opening, the grille being held by screws, cement or frictionally fitted as is desired. There is never any necessity for having access to both sides of the door in order to emplace the grille.

30 Other and more general objects of the invention are to provide a grille of simple, practical construction, which will be neat and attractive in appearance, rugged, durable and efficient in use, and well suited to the requirements of economical manufacture.

With the above and other noted objects in view, the invention consists in certain novel features of construction and combinations and arrangements of parts, as will be more fully

hereinafter set forth and pointed out in the 55 claims. The invention may be more fully understood from the following description in connection with the accompanying drawings, wherein—

Fig. 1 is an outside plan view showing 60 the grille of the present invention attached to a door.

Fig. 2 is an inside plan view with parts broken away and in section for clearness.

Fig. 3 is a transverse sectional view on the 65 line 3—3 of Fig. 2.

Fig. 4 is a sectional plan view illustrating a slightly modified form of grille and the method of attaching it to a door.

Fig. 5 is a similar view illustrating a further modification.

Referring first to Figs. 1 to 3 inclusive of the drawings, I have used the reference numeral 10 to designate a door, and 11 an opening preferably of circular shape which 75 is cut in the door. The grilles are particularly suited for use in connection with thin metal fire-proof doors, and are designed to comply with all the requirements of the fire laws. An opening frame member 12 is 80 adapted to snugly fit within the opening 11 and includes a flanged portion 13 overlying the outer face of the door. Frame member 12 is preferably integrally cross barred as at 85 14 and the flange 13 is provided with suitable openings through which securing screws or equivalent securing devices 15 are adapted to be passed. If desired, the screws may be passed through the radially extended ear portions 16 of the flange 13.

90 Projecting inwardly from the rear face of the ring 12 are a pair of spaced ears 17 receiving between them spaced ears 18 on a circular closure plate 19. A hinge pin 20 passes through aligned pairs of ears 17 and 18 and the exposed intermediate portion of the hinge pin is preferably encircled by a coiled torsional spring 21 urging the closure plate 19 to closed position.

The portion of the closure 19 opposite its 100 hinged portion carries a sliding bolt 22 mounted in a sleeve 23 integral with the closure and normally projected by a spring 24 pocked in the inner end of the sleeve. The shank 25 of an operating handle 26 105 works in a slot 27 in the sleeve, and the pocket end of the bolt is provided with an inclined face 28 for coaction with a keeper

member 29 on the ring 12 in order that the bolt may automatically latch as the closure is urged to closed position by the spring 21.

Preferably, in order to avoid a draft through the grille the central portion of the closure plate is offset as at 30 to snugly fit within the ring 12.

In Fig. 4 I have illustrated a slightly modified form of the invention in which the ears 16 and the screws 15 may be omitted. Here a ring 12^a and flange 13^a correspond to the ring 12 and flange 13 of Fig. 1. The grille unit is inserted from one side of the door into a prepared opening 11^a and retained by the use of a suitable cement 31 which connects the ring and flange to the outer face of the door and the walls of the opening.

In Fig. 5 I have illustrated a further modification wherein the door opening 11^b is tapered, the flange 13 is omitted and the ring 12^b is tapered in order that it may be frictionally fitted into the tapered opening.

It will be noted that in all three forms of the invention, the barred frame plate and its closure are previously assembled and then applied as a unit to the door by the simple expedient of inserting the grille unit into the opening where it may be secured by a friction fit, cement or screws.

Obviously, various changes and alterations might be made in the general form and arrangement of the parts described without departing from the invention. Hence I do not wish to limit myself to the details set forth, but shall consider myself at liberty to make such changes and alterations as fairly fall within the spirit and scope of the appended claims.

40 I claim:

1. A two-piece grille unit adapted to be assembled and subsequently bodily emplaced and secured in an opening in a door or the like from one side of the door, and including a cross barred frame member fitting the opening and a closure member pivotally connected to one side of the inner face of the frame and coacting with latching means carried by the free portion of the closure

and the other side of the inner face of the 50 frame.

2. A two-piece grille unit adapted to be assembled and subsequently bodily emplaced and secured in an opening in a door or the like from one side of the door, and including a cross barred frame member fitting the opening and a closure member pivotally connected to one side of the inner face of the frame and coacting with latching means carried by the free portion of the closure 60 and the other side of the inner face of the frame, the frame including means for limiting the entrance of the grille unit into the opening.

3. A two-piece grille unit adapted to be assembled and subsequently bodily emplaced and secured in an opening in a door or the like from one side of the door, and including a cross barred frame member fitting the opening and a movable closure member 70 mounted on the inner face of the frame, the frame and opening being similarly tapered whereby the grille unit may be force-fitted into the opening.

4. A two-piece grille unit adapted to be 75 assembled and subsequently bodily emplaced and secured in an opening in a door or the like from one side of the door, and including a cross barred frame member fitting the opening and a closure member pivotally 80 connected to one side of the inner face of the frame, coacting with latching means carried by the free portion of the closure and the other side of the inner face of the frame, the frame frictionally fitting within 85 the opening.

5. A two-piece grille unit adapted to be assembled and bodily emplaced in an opening in a door or the like from one side of the door, the unit including a frame portion 90 adapted to fit within the opening, and a movable closure member mounted on the inner side of the frame, the closure member being wholly confined within the area of the opening whereby the unit may be inserted bodily into the opening.

GEORGE W. ACKERMAN.
